STRIP-GUIDING AND SEVERING DEVICE
FOR SEWING MACHINES

James E. Ackerman, Devon, and Charles R. Odermann, Milford, Conn., assignors to The Singer Manufacturing Company, Elizabeth, N. J., a corporation of New Jersey

Application November 30, 1950, Serial No. 198,274

8 Claims. (Cl. 112—136)

1

This invention relates to sewing machine strip-guiding devices and has particular reference to devices of this character which adapt the sewing machine for such operations as the application of covering cross-strips or bands incident to the connection of bibs to the trousers of overalls.

In stitching the covering cross-strip to the inner face of the overalls, it is desirable that the cross-strip be of such length that its opposite ends are short of the marginal side edges of the garment, so that in the edge hemming operations to follow, the cross-strip will not be included in the hem, but its ends will be covered and concealed by the inner fold edge of the hem.

Heretofore, one of two methods was commonly used in obtaining the above described shortened cross-strip. One of these methods included the steps of sewing the cross-strip to a plurality of garments in a continuous fashion, and in a subsequent operation ripping the seams back from the marginal edges of each garment to prepare the cross-strip so that it could be cut by hand. The ripping of the seam is an expensive operation since it had to be done on both sides of each garment, and the short length of cross-strip connecting successive garments had to be thrown away. Another method employed involved the use of a so-called strip-collapsing attachment on the sewing machine which was designed so that at the proper time in the stitching cycle, the marginal edges of the cross-strip could be collapsed out of the range of the needles, and thus not stitched to the garment. While this latter method eliminated the need for the seam ripping operation, it did not eliminate the waste of the cross-strip and it required the use of a rather complicated strip-collapsing attachment.

It is the primary object of the present invention to provide a simple strip-guide equipped with a manually actuated strip-severing means operable at the will of the operator to sever the cross-strip at the desired point immediately in advance of the point where it is stitched to the garment.

A further object is to provide, in a guiding device adapted to assist in forming a seam including a reinforcing-strip, a practical and efficient means whereby the strip may be severed and reintroduced during the formation of the seam at the discretion of the sewing machine operator.

Still another object of this invention is to provide a strip-guiding and severing device of the above described character, together with actu-

2

ating mechanism therefor, which is constructed and arranged to permit ready attachment and removal from a sewing machine.

With the above and other objects in view as will hereinafter appear, the invention comprises the devices, combinations, and arrangement of parts hereinafter set forth and illustrated in the accompanying drawings of a preferred embodiment of the invention, and the advantages attained thereby will be readily understood by those skilled in the art.

In the drawings:

Fig. 1 is a front elevational view of a portion of a sewing machine having my attachment applied thereto;

Fig. 2 is a bottom plan view, partly in section, of my attachment;

Fig. 3 is a sectional view taken substantially along line 3—3 of Fig. 1;

Fig. 4 is a top plan view of a portion of the sewing machine with my attachment applied thereto, a part of the sewing machine bed being broken away better to illustrate the details of the attachment;

Fig. 5 is a top plan view principally of the strip-guiding and strip-reintroducing portions of my attachment with the supports therefor and the knife holder taken in horizontal section.

Fig. 6 is a sectional view taken substantially along line 6—6 of Fig. 3, illustrating particularly the disposition of the cutting blade; and

Fig. 7 represents a bottom plan view of a portion of the work produced with the aid of my attachment.

In the drawings, the invention is shown as applied to a sewing machine of the type disclosed in the U. S. patent of Zeier No. 2,312,858, March 2, 1943, which comprises, generally, a bed 10 from which rises a standard 11 supporting an overhanging arm 12. Journaled for reciprocation in the overhanging arm is a needle-bar 14 and secured thereto are needles 15—15. Also supported from the overhanging arm is a presser-foot 16. Secured to the bed 10 are a plurality of work-supporting plates 17, 18, of which plate 17 is apertured to accommodate a throat-plate 19 and a slide-plate 20. Located within the bed 10 are loopers 21 which are complementary to the needles 15—15 and operated by suitable actuating mechanism. A feed-dog 22, as shown in Figs. 3 and 4, is disposed to operate through slots 23 in the throat-plate 19 to advance the work past the stitch-forming instrumentalities in the usual manner.

The work-plate 17, at the sides of the aperture

formed therein to accommodate the slide-plate 20, is formed with lips 24-24. Spring clips 25-25 are attached beneath the slide-plate, one at either side thereof, to extend beneath and yieldingly engage the lips 24-24, thereby to secure the slide-plate to the work-plate 17. In order that the slide-plate may be locked in position, a latch-spring 26 is secured to work-plate 17 at 27 and is formed at its free end with a detent 28, Fig. 3, which enters a slot 29 in the slide-plate. A latch release pin 30 extends upwardly from the latch-spring through an aperture 31 formed in the work-plate 17. When the pin 30 is depressed, the detent 28 is also lowered out of engagement with the slot 29 and the slide-plate may be withdrawn.

In carrying out my invention, as will be described in detail below, I prefer to secure to the slide-plate 20 as a unitary assembly, a guiding and folding device for both body fabrics to be united, a guide for the reinforcing strip, a device for at will severing the strip, and a mechanism for controlling the strip after it has been severed. Then to the bed of the sewing machine I secure the actuating mechanism for the strip cutting device, and provide between the actuating mechanism and the cutter a means for conveniently separating or reuniting the two in order that the slide-plate and the parts secured thereto may be readily removed and replaced.

The means for directing a reinforcing strip from beneath the slide-plate to the stitching point comprises a tubular sheet-metal guide, indicated generally as 32. The guide extends upwardly through an opening 34 in the slide-plate and is formed with scrolls 33-33 for inturning the marginal edges of the reinforcing strip. Support members 35-35 extend laterally from the guide 32 and each is formed to receive a fastening screw 36-36 by which the guide is secured to a Y-shaped bracket 37, Fig. 1. Spaced upstanding limbs 38-38 of the bracket 37, Fig. 3, are arranged to abut correspondingly spaced downturned ears 39-39 which depend from the slide-plate 20 so that by means of fastening screws 40-40, the bracket 37 is rigidly secured in place.

An edge-guide 41 and an edge-folding guide 42 are secured above the slide-plate 20 and arranged to direct the marginal edges of two panels of garment fabric in proper lapped and folded relation above the delivery end of the strip-guide 32 so that a seam of the type illustrated in Fig. 7 may be formed. To this end, edge-guide 41 of which the forward extremity is recessed as at 43 to accommodate the strip-guide 32, is formed with a base portion 44 which is slotted as at 45-45 to receive fastening screws 46-46 which are threaded into the slide-plate 20. By means of the slots 45-45, the edge-guide 41 may be adjusted toward or away from the needles. The edge-folding guide 42 is disposed to overlie the edge-guide 41, and is provided with a shank portion 47 slotted as at 48-48 to receive fastening screws 49-49 which are threaded into the base portion 44 of edge-guide 41. The folding-guide 42, therefore, will partake of any adjustment of the guide 41 toward or away from the needles, and by means of slots 48-48 a limited lateral adjustment of guide 42 is possible independently of the guide 41.

The mechanism of the present invention for severing the reinforcing strip comprises a single knife blade 50 having a cutting edge 51. The blade is secured by means of a clamping-screw 52 within a recess 55 formed in an inclined face 54 of a knife carrying slide-block 53 so that the

blade 50 is disposed in a plane substantially perpendicular to the strip-guide 32. As shown clearly in Fig. 6, the recess 55 is inclined with respect to a line perpendicular to the strip-guide so that the blade 50 is supported with the cutting edge 51 similarly inclined.

The knife carrying slide-block 53 is confined to movement transversely of the strip-guide by means of two parallel guide-bars 56-56 which are secured beneath the slide-plate 20 by means of fastening screws 57-57. The guide-bars are formed with grooves 58-58 which receive tongues 59-59 extending from the knife carrier 53.

To accommodate the blade 50, the strip-guide is separated intermediate its ends into two parts which are spaced to form a narrow transverse slot 60. One part of the separated guide extends between the slot 60 and the stitching point and will be hereinafter referred to as the delivery portion of the guide, while the second part of the guide which extends between the slot and the strip-receiving end of the guide will be termed the receiving portion. The two parts of the guide are bridged externally by a U-shaped member 61, which in addition to maintaining the guide parts in spaced relation, provides a channel which is entered by the lower free extremity of the blade 50 to stabilize the free extremity of the blade. The member 61 supports the delivery portion of the strip-guide from the receiving portion and also extends laterally on each side of the strip-guide so as to provide a continuous support for the lower extremity of the cutting blade.

The advantages attained by virtue of the instant combination of a strip-guide which is separated between its ends, together with the use of an inclined-edge knife disposed to pass between the guide portions, are manifold; the employment of an inclined knife edge results in a smoother cutting action, and since the separated strip-guide supports the strip at each side of the path of the blade, the tendency for the blade to shift or distort the fold-edges of the strip during severance is minimized, thus producing a more evenly severed edge. Furthermore, with the instant arrangement, should the strip be shifted laterally during severance, the delivery portion of the guide, which acts upon the strip from the point at which it is severed to the stitching point, will cause the strip to be realigned in the guide before it emerges and is incorporated into the seam.

Carried by the bed of the machine is an actuating linkage by which the blade 50 may be at will advanced and retracted transversely across the strip-guide. The linkage is supported by a plate 62 which is secured to the bed of the machine by means of fastening screws 63 and 64. A lever 65 of the first class is pivoted to turn about the screw 63 and is provided at its lower extremity with a suitable connection to a knee-shifter or foot treadle, such as by rod 66. At the upper extremity of lever 65, there is pivoted a roller 67 which engages a vertical slot 68 in a movable slide-bar 69 which is shiftable laterally in response to movements of lever 65. The bar 69 enters a horizontal guiding recess 71 formed in the plate 62 and is provided with a horizontal clearance slot 70 for a screw 72 which retains the bar 69 for horizontal sliding movements within recess 71.

In order that the slide-plate 20 and the cutting blade carried thereby may be readily removed from and replaced on the sewing machine, a separable connection is provided between the actuating linkage and the cutting blade. To this

end, the bar 69 is formed with a projecting ear 73 in which a notch 74 is provided. A connecting member 75, which is secured at one extremity beneath the slide-block 53, is formed at its free extremity with a depending lug 76 which is adapted to enter the notch 74 to provide a readily separable yet positive driving connection between the actuating mechanism and the cutter.

To prevent inadvertent movement of the blade 50, a spring 77 is secured to the connecting member 75. A detent 78 is formed at the free extremity of the spring which is positioned such that when the blade occupies the retracted position, as shown in full lines of Fig. 6, the detent 78 engages the end of the guide bar 56. The spring 77 is of sufficient stiffness to prevent accidental movement of the cutting blade, as from vibration of the sewing machine, etc.; but nevertheless is sufficiently flexible so as to offer negligible resistance to movement of the blade when properly urged by the actuating linkage.

After the reinforcing strip is severed, the part of the strip which remains in the receiving portion of the strip-guide will cease to be advanced by the sewing machine feed-mechanism. In order to prevent this part of the strip from dropping out of the receiving portion of the guide 32 and to provide a means for reintroducing the strip to the stitching point at the will of the operator, the upper surface of the tubular strip-guide 32 is formed with an elongated opening 79 through which extends a spring-finger 80 which is formed with serrations 81 at its forward extremity. The spring-finger 80 is secured at its rearward extremity to a block 82 which is in turn pivotally connected to one end of a lever 83 by means of a screw 84 and a slot 85 formed in lever 83. The lever is pivoted to the bracket 37 by means of a stud 86 about which is disposed a coil spring 87 one end of which engages a lug 88 of the bracket 37, while the other end of the coil spring is fastened to the lever 83 to bias the lever into its retracted position. The block 82 is confined within a guide slot 89 formed in bracket 37 parallel to the opening 79 in the strip-guide, so that when a turning movement is imparted to the lever 83, as by means of a handle 90 secured at the free extremity thereof, the block 82 and the spring-finger 80 will move parallel to the strip-guide as may be clearly discerned in Fig. 5. The maximum distance which the spring finger may move corresponds to the distance between the transverse path of the cutting blade and the stitching point of the sewing machine so that by turning the lever 83, a severed strip may be reintroduced to the stitching point. It will be understood that the spring-finger is biased downwardly against the lower surface of the strip-guide. A finger-grip 91 is provided for manually lifting the spring finger so as to facilitate loading of the strip.

The above described preferred embodiment may be applied to a sewing machine simply by replacing the usual slide-plate with a slide-plate having the present invention attached. In assembly, it is necessary only to insure that the lug 76 of the cutting-blade connecting-member is positioned to enter the notch 74 of the movable actuating bar 69.

In order to produce a reinforced seam of which the reinforcing-strip terminates at each side short of the side edge of the garment, as illustrated in Fig. 7, the operator first directs the marginal edges of two garment panels A&B to the stitching point through guides 41 and 42. Sewing is

then begun and continued for a distance necessary for the completion of a side hem in a later operation. At this point, the operator turns lever 83 by means of handle 90 thereby sliding the spring-finger 80 forward, the serrated extremity of which grips the reinforcing strip S and advances the strip to the stitching point. Once introduced, the strip is joined by stitches to the garment panels and is thereafter advanced by means of the usual sewing machine feed mechanism. Sewing is continued until a point has been reached at which the strip must be severed in order that it will terminate at the desired distance from the side edge of the garment. At this point, the operator actuates the strip cutting mechanism as by a knee-shifter or foot-treadle to move the blade 50 across the slot 60 in the strip-guide 32, thus severing the reinforcing strip. Usually knee-shifters or foot-treadles are spring biased into retracted position, and therefore no such spring has been incorporated in the preferred embodiment of my invention, it being understood that any such suitable means for retracting the blade 50 may be employed. The portion of the severed strip which leads to the supply is retained within the guide 32 against retrograde movement by the serrated spring-finger 80 in readiness for the succeeding reintroduction to the seam. Sewing of the original garment seam is continued past the severed edge of the reinforcing strip and to the edge of the garment panels thus completing one cycle of operation.

The sewing machine operator must judge the proper point during the sewing operation for the introduction and severing of the reinforcing strip, and the necessary skill is quickly developed whereby the formation of reinforced seams with the invention becomes substantially a continuous operation.

Having thus set forth the nature of the invention, what we claim herein is:

1. In a sewing machine having a work-support provided with an opening, an attachment for directing the edges of a plurality of body fabrics and a reinforcing-strip to the stitching point so as to produce a reinforced seam, said attachment comprising a slide-plate adapted to be positioned in said opening, work-guides carried at one side of said slide-plate in position to direct the edges of said body-fabrics to the stitching point in predetermined relative relation, a strip-guide secured to said slide-plate at the side opposite said work-guides, a movable strip-cutter supported by said slide-plate and adapted to sever said reinforcing-strip intermediate the ends of said strip-guide, actuating mechanism carried by said sewing machine work-support for imparting movement to said strip-cutter, and a separable positive driving connection between said strip-cutter and said cutter actuating mechanism for facilitating removal and replacement of said attachment.

2. In a sewing machine having a work-support provided with an opening, an attachment comprising a supporting plate adapted to be slidably positioned in said opening, work-guiding instrumentalities including a strip-guide for directing a plurality of plies of body fabric and a reinforcing strip to the stitching point of the sewing machine to produce a reinforced seam, a strip-cutter slidably secured to said supporting plate for translatory movement in a path transversely of said strip-guide, cutter actuating mechanism including a member carried by said sewing machine work-support for translatory move-

ment in a direction substantially parallel to the path of movement of said strip-cutter, and separable coupling means between said strip-cutter and said actuating member and arranged to provide a positive driving connection between said strip-cutter and said actuating member when said supporting plate is normally positioned in said sewing machine work-support opening.

3. A strip-guiding and severing device comprising a plurality of work guides, a strip-guide associated with said work guides, said strip-guide having surfaces arranged to maintain a substantial portion of said strip in a single plane during the passage of the strip through the guide, a knife-carrier supported for movement crosswise of said strip-guide in a path substantially parallel to the plane of said strip, a strip-cutting knife blade having a cutting edge inclined to the plane of the strip in the plane of movement of the knife-carrier, a knife-locating seat formed on said knife-carrier, and a clamp member associated with said knife-carrier for securing said knife against said locating seat.

4. An attachment adapted for a sewing machine having a work-support provided with an opening, comprising a slide-plate adapted to be positioned in said opening, work-guides secured above said slide-plate in position to direct the edges of a plurality of plies of body fabric into predetermined relative relation, a flat tubular strip-guide secured beneath said slide-plate so as to direct a reinforcing strip into lapped relation with the edges of said body fabrics, said strip-guide separated transversely into a strip-receiving part and a strip-delivery part, a connecting member arranged externally of said strip-guide and maintaining the two parts thereof in aligned spaced relation, a knife-carrier supported beneath said slide-plate for sliding movement transversely of said strip-guide, a knife-blade supported at one extremity by said knife-carrier and having a free extremity adapted to move between the proximate ends of said separated strip-receiving and strip-delivery parts to sever said reinforcing strip, a knife-blade actuating linkage including a slide-bar carried by said work-support for movement in a direction parallel to said knife-carrier, projections extending from said slide-bar and from said knife-carrier, said projections disposed to interlock when said slide-plate is positioned in said work-plate opening so as to provide a positive knife-blade driving connection, and strip-controlling mechanism independent of the knife-blade actuating linkage for preventing retrograde movement of the strip which remains in the receiving end of the guide after severance and for causing said remaining strip to be reintroduced to the action of the sewing machine, said strip-controlling mechanism including a manually operable lever, a slide-block supported for movement in the direction of movement of the strip through the guide, and a spring finger extending from said slide-block toward the sewing machine, said spring finger having a free extremity adapted to enter said strip-receiving part of the strip-guide and bear against said reinforcing strip.

5. A work-presenting attachment for a sewing machine having a machine-frame, comprising, a supporting member adapted to be detachably sustained by said machine-frame, work-guides secured to said supporting member in position to direct the marginal edges of a plurality of body fabrics into predetermined relative relation, a strip-guide secured to said support-

ing member so as to direct a reinforcing strip into lapped relation with the marginal edges of said body fabrics, said strip-guide being transversely divided intermediate its ends into tandem arranged strip-receiving and strip-delivery sections, a knife-carrier slidably mounted on said supporting member for movement transversely of said strip-guide, a knife-blade secured to said carrier and disposed to move between the proximate ends of said separated strip-receiving and strip-delivery sections of said strip-guide to sever said fabric strip, knife-actuating mechanism attached to said machine-frame, and separable coupling means disposed between said knife-carrier and said knife-actuating mechanism and arranged to readily part when said supporting member is detached from said machine-frame enabling the supporting member and its guides to be removed as a unit.

6. A work-presenting attachment for a sewing machine having a machine-frame, comprising, a supporting member adapted to be detachably sustained by said machine-frame, work-guides secured to said supporting member in position to direct the marginal edges of a plurality of body fabrics into predetermined relative relation, a strip-guide secured to said supporting member so as to direct a reinforcing strip into lapped relation with the marginal edges of said body fabrics, said strip-guide being transversely divided intermediate its ends into tandem arranged strip-receiving and strip-delivery sections, a strip-severing device attached to said supporting member and disposed to operate between the proximate ends of said separated strip-receiving and strip-delivery sections of said strip-guide to sever said fabric-strip, strip-severing device actuating mechanism attached to said machine-frame, and separable coupling means disposed between said strip-severing device and said knife-actuating mechanism and arranged to readily part when said supporting member is detached from said machine-frame enabling the supporting member and its guides to be removed as a unit.

7. A reinforced seam forming attachment for sewing machines comprising a supporting member, work guides carried by said supporting member in position to direct the edges of a plurality of plies of body fabric to the stitching point of the sewing machine in predetermined relative relation, a strip-guide carried by said supporting member in spaced relation thereto so as to direct a reinforcing strip into lapped relation with the edges of said body fabrics, a knife carrier, parallel knife carrier guide-ways disposed between said strip-guide and said supporting member and extending transversely beyond each side of said strip guide, and a strip cutting knife blade rigidly secured to said knife-carrier and adapted to sever said reinforcing strip at a point between the ends of said strip guide.

8. A reinforced seam forming attachment for sewing machines comprising a supporting member, work guides carried by said supporting member in position to direct the edges of a plurality of plies of body fabric to the stitching point of the sewing machine in predetermined relation, two tubular strip-guiding members arranged to operate in seriatim to direct a reinforcing strip into lapped relation with the edges of said body fabrics, a connecting member arranged at one side of said strip-guides and maintaining said guides in spaced relation in the direction of

movement of the strip through the guides, a knife-carrier slidably supported for translatory movement in a path across the strip guiding members at the side of said strip-guides opposite said connecting member, a knife stabilizing channel formed in said guide connecting member parallel to the path of movement of said knife carrier, and a strip cutting blade supported at one extremity by said knife carrier and at the opposite extremity by said stabilizing channel.
